AMOS CALLESON, OF BROOKLYN, NEW YORK, ASSIGNEE TO ADRIANCE MACHINE WORKS, INC., OF BROOKLYN, NEW YORK, A CORPORATION OF NEW YORK.

BOTTLE-FEEDING MECHANISM.

Specification of Letters Patent. Patented July 15, 1919.

1,309,935.

Application filed December 15, 1917. Serial No. 207,224.

To all whom it may concern:

Be it known that I, AMOS CALLESON, a citizen of the United States, residing at Brooklyn, in the county of Kings and State of New York, have invented certain new and useful Improvements in Bottle-Feeding Mechanisms, of which the following is a specification.

This invention relates to means for advancing articles, as bottles, step by step, and it consists, first, in a novel construction of rotary advancer or turret adapted to be adjusted to suit different sizes of the articles to be advanced, and, second, in a novel means 15 for effecting step by step movements of the advancer.

In the drawings,

Figure 1 is a plan of the mechanism;

Fig. 2 is a vertical sectional view thereof;

Fig. 3 is a plan and Fig. 4 a vertical sectional view of the body part of the rotary advancer or turret;

Fig. 5 is a plan and Fig. 6 a vertical sectional view of the head-block for the axial shaft depending from said advancer or turret;

Fig. 7 is a horizontal sectional view in the plane of line 7-7 of Fig. 2;

Fig. 8 is a plan of the advancer or turret, the same being formed in two—upper and lower—parts;

Figs. 9 and 10 are vertical sectional views of said parts;

Fig. 11 is a side elevation of a fragment of 35 said parts, showing the hinge-portion for a certain hinged spring-finger; and

Figs. 12, 13 and 14 are side, plan and edge views of said finger.

To the frame *a* of a bottle filling and sealing machine is secured in any suitable manner a bracket *b* upon which rests a plate *c* having a yielding bottle-pad or seat *d*. A cylindrical bearing member *e* is supported by its flange *f* resting on the top of the bracket, being penetrated by a stout pin or shaft *g* which is supported by a head-block *h* (Figs. 5 and 6) which is keyed on the upper end of said shaft. The lower end of the shaft has affixed thereto the ratchet *i*.

Journalized on member *e* above the ratchet is a crank *j* carrying a spring-pressed pivoted pawl *k* normally engaging the teeth of the ratchet, *l* being a link whereby from a suitably oscillated crank *m*, the pawl is oscillated. The rotary structure including shaft

g and all the parts carried by it is kept from moving beyond a definite point on each pick of the pawl (on account of the impetus received from the pawl) by a stop *n* which at the end of the pawl's working stroke holds the latter against the ratchet and so in the path of the tooth next back of that it is engaging; this stop is the off-turned end of a bolt *o* which by means of a handle *p* can be turned in bracket *b* so that the stop clears the pawl, thus to permit the rotary structure to be turned by hand with the pawl at the end of its working stroke.

The centering body part of the turret or advancer is arranged on and secured to the head-block *h* thus: It is formed in two parts, the base or lower part *q* and the upper or annular part *r*. Part *q* is a casting hollowed out at the under side (as at *q'*) to fit snugly over the head-block and having a circumferential outer rabbet *q''* at the top and a circumferential outer flange *q''* at the bottom. Part *r* is arranged in the rabbet and projects so that it and the flange *q''* form a circumferential groove *s*. At equidistant points parts *q* and *r* are secured in permanently fixed relation to each other by screws *t*, which are tapped into head block *h* and penetrate spacing sleeves *u* serving to space the parts *q* *r* in the annular line of the screws a slight distance as indicated at *u'* in Fig. 4; outwardly of this spacing means, therefore, the parts may be sprung together upon the application of suitable pressure, with the effect of somewhat reducing the width of groove *s*. Parts *q* and *r* further afford bearings for the arbors *v* of a pair of intermeshing pinions *w*, the upper end of one arbor being exposed and formed square to receive a wrench.

Two annular sections or rings *x*, *y*, one upon the other, embrace the centering body part of the turret, being engaged in groove *s*, as shown in Fig. 2. They have toothed segments *x'*, *y'* engaged with the two pinions *w*, respectively. By operating the gearing constituted by the pinions, that is, by turning the pinions in their bearings it will be apparent that the rings *x*, *y* will be moved rotatively relatively to each other in opposite directions. To hold the rings in the position to which they are adjusted I provide clamping screws *z* arranged equidistantly and penetrating freely the annular part *r* but fixed in the part *q* of the center-

ing body member and having nuts z' on their upper ends, they being arranged so as to pass through the space s and thus be adapted on tightening the nuts to spring the outer 5 circumferential portion of part r toward the flange q^3 and clamp the two rings x, y between them. It will be observed that, when nuts z' are released, the screws t retain parts q, r fast, particularly so that the proper 10 working position of the pinions w will not be disturbed.

Each ring x, y has projections forming bottle supporting devices and projecting radially therefrom in different radii. The 15 projections 2 on the ring x and those 3 on ring y are respectively extended, the former down and the latter up, so that the extension of each projection z on ring x , for example, is in the rotary path of the two projections 20 3 on the other ring flanking it. Thus the bottle, which stands between each two projections 2-3, has ample lateral support against upsetting. The projections 3 are curved (their concave or bottle engaging 25 sides) being faced in the direction of rotation; the projections 2 have hinged spring-fingers or gates 4 at their free ends (5 being a spring-pressed plug housed in the projection 2 and normally holding the gate at 30 a limit which the plug itself affords—Figs. 8 and 13—while allowing it to swing outwardly). By adjusting the rings x, y rotatively, as described, the distance between each two projections 2, 3 can be altered to 35 suit the size of bottle being advanced. The bottles are entered downwardly into the pockets formed by the projections, and at the proper point in the rotation of the turret are drawn radially outward clear of the 40 turret, the spring-fingers 4 yielding to them.

At equidistant points the ring y has a wiping blade 7 projecting in a chord of the circular path of the bottles, the same acting to wipe off of the bottle seat h and out 45 of the pockets formed by the projections fragments of bottles which may become broken while they are being operated upon on said seat.

Having thus fully described my invention, what I claim as new and desire to secure by Letters Patent is:—

1. A rotary advancer including a centering body member divided transversely of the axis of rotation of the advancer into two 55 parts, separate sections arranged between

said parts and having article-supporting devices in different radii, and means to draw said parts together to clamp said sections between them, one of said sections being rotatably adjustable relatively to the other 60 when unclamped.

2. A rotary advancer including two sections having article-supporting devices on each of them in different radii, one of said sections being rotatable relatively to the 65 other on the axis of rotation of the advancer, and gearing to shift the rotatable section relatively to the other around said axis.

3. A rotary advancer including a rotary centering body member, two sections arranged 70 on said member and having article-supporting devices in different radii and each being rotatable on said member around the axis of rotation of the advancer, and gearing to adjust said sections in opposite 75 directions around said axis.

4. A rotary advancer including a centering body member, two sections arranged 80 on said member and having article-supporting devices in different radii and each being rotatable on said member around the axis of rotation of the advancer, and means to adjust said sections in opposite directions around said axis including gearing having oppositely rotating gear members respectively 85 engaging said sections.

5. A rotary advancer including a centering body member divided transversely of the axis of rotation of the advancer into two parts and having means to secure said parts 90 together in fixed relation to each other, said parts forming a groove extending around said axis, a structure having article-supporting devices and embracing and rotatably adjustable on said member and engaged in 95 the groove thereof, and means to draw the portions of said parts at both sides of the groove into clamping relation to the part of said structure engaged in the groove.

6. In combination, with a flat support 100 for the bottles, a rotary bottle advancing turret arranged to rotate over the surface of the support on a vertical axis and having peripheral bottle receiving pockets, and also having wipers projecting therefrom each in 105 a chord across the circular path of said pockets.

In testimony whereof I affix my signature.

AMOS CALLESON.
